FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

PAD HOLDER OR CASE.

1,273,353.

Specification of Letters Patent. Patented July 23, 1918.

Application filed October 3, 1916. Serial No. 123,489.

To all whom it may concern:

Be it known that I, FRANZ A. FULLER, a citizen of the United States, residing in the city of Newark, in the county of Essex and State of New Jersey, have invented certain new and useful Improvements in Pad Holders or Cases, of which the following is a full, clear, and exact description, such as will enable others skilled in the art to which it pertains to make, construct, and use the same, reference being had to the accompanying drawings, and to letters of reference marked thereon, forming a part of this specification.

This invention has for its object to provide a pad holder or case adapted for the reception of small pads. My improved pad holder or case is of such form that it is well adapted for advertising purposes, in that the advertisements may be placed or embossed in any suitable manner on the back and the lid thereof, and the case is of such convenient and attractive form as to render it desirable to be retained permanently by the user, and to be refilled by the pad as often as the same becomes exhausted; or the case may be used, owing to its novel construction, to contain stamps, visiting or business cards, railroad tickets, change or the like.

A further object of my invention is to provide a pad holder or case, provided with a spring-actuated intermediate plate, hingedly connected to the back portion of the case and the lid thereof, in such a manner that the contents of said case will, by means of said intermediate spring actuated plate, be firmly held in said case by the spring pressure exerted by said intermediate plate, and at the same time, permit the ready removal or withdrawal of cards or the like, from the case when the lid thereof is open. The employment of the spring-actuated intermediate plate serves to frictionally hold one end of the pad, preferably the stub end thereof, or one end of the cards, so that when the lid is opened, the cards or pad cannot become accidentally displaced from said case, by reason of said plate, but a single card or a single leaf of the pad can be removed therefrom, without disturbing the remainder of the cards or the pad.

In the accompanying drawings—

Figure 1 represents a front view of my improved memorandum case closed.

Fig. 2 represents a similar view of the same, open.

Fig. 3 represents a side elevation of the same; and

Fig. 4 represents a longitudinal section of the improved case taken on line $x-x$ of Fig. 1, illustrating the lid in full lines in partly open position, and illustrating in dotted lines, the lid and the intermediate plate in a position to enable the pad or a number of cards to be placed in the case.

Similar letters of reference refer to like parts throughout the specification and drawings.

The improved pad holder or case is preferably made of flexible sheet metal of any kind, such as brass, tin, copper or aluminium.

The body of the case comprises a back portion a , the top of which is provided with tubular bearings $b-b$, and the longitudinal edges of which are provided with upwardly extending flanges $c-c$. To one of the upwardly-extending flanges c , a tubular pencil-receiving element d is secured in any suitable or convenient manner. The lid e of the case at its upper edge, is also provided with tubular bearings $f-f$, corresponding to the tubular bearings $b-b$ formed on the top of the back portion a , the purposes of which will be hereinafter described, and the lower portion of the lid is provided with a downwardly-extending flange g , which when the lid e is in closed position, preferably abuts against the inner face of the back portion a , as clearly indicated in Fig. 3 of the drawings, thereby forming a closed compartment.

The lid e , on the inside thereof, and extending inwardly from the longitudinal edges thereof, is provided with preferably integral inwardly-extending channels $h-h$, providing holding or receiving means for advertising matter, railroad tickets, a mirror or the like.

Secured to the tubular bearings $b-b$ of the back portion a , and to the tubular bearings $f-f$ of the lid e , is an intermediate plate i , one longitudinal edge of which is provided with tubular bearings $j-j$, and the other longitudinal edge being provided with the tubular bearings $j'-j'$, similar to the tubular bearings formed on the back portion a and lid e .

The plate i , by means of the tubular bear-

110

ings $j-j$, is hingedly connected to the tubular bearings $b-b$ of the back portion a , by means of a pintle k , and also hingedly connected to the lid e by means of the tubular bearings $j'-j'$, which are hingedly connected to the tubular bearings $f-f$ of the lid e by means of a pintle l .

Surrounding the pintle k is a spiral spring m , one end of which bears against the back portion a , and the other end of which bears against the plate i , which spring tends to keep the plate i in engagement with the memorandum pad n . A similar spring o surrounds the pintle l , one end of which bears against the plate i and the other end of which bears against the lid e , which will tend to keep the lid e in its closed position.

The stub of the pad n is held in position on the back portion a of the case by the spring-actuated plate i , by means of the spring m , and the lid e is normally held in closed engagement with the case by means of the spring o .

The parts are of such shape as to lend themselves readily to manufacture by the use of suitable punches and dies from ordinary sheet metal.

The spiral spring m normally tends to prevent the plate i from being raised away from the stub of the pad or a number of cards, so that any cards or the pad contained in the case, are frictionally held in the case by said plate i , but by applying pressure to the lid e , the plate i will be caused to swing about the pintle k , thereby freeing it from the cards or the stub of the pad, in order that the same may be replaced or removed from the case.

Experience has demonstrated that the organization above described is a highly efficient one, and while the device described is the preferred embodiment of my present invention, I do not care to restrict myself to

the exact details of construction, combination and arrangement herein set forth, it being obvious that minor variations thereof, not involving the exercise of invention, may be made by any skilled mechanic, and such departures from what is herein described and claimed, I consider within the scope and terms of my claims.

I claim:

1. A pad holder or case comprising a back portion, the top of which is provided with an integral upturned bearing, and the longitudinal edges of which are provided with upwardly-extending flanges, a spring-actuated lid, provided at one end with tubular bearings and at its opposite end with a flange, designed to engage with the said back portion, and a spring-actuated intermediate plate having integral bearings, hingedly connected to the bearings of the back portion and the spring-actuated lid.

2. A pad holder or case comprising a back portion, the top of which is provided with an integral upturned bearing, and the longitudinal edges of which are provided with upwardly-extending flanges, a spring-actuated lid provided at one end with an integral bearing and receiving channels formed along the longitudinal edges thereof, the lower portion of the lid being provided with a downwardly-extending flange adapted to abut against the back portion, and a spring-actuated intermediate plate having integral bearings, hingedly connected to the bearings of the back portion and the spring-actuated lid.

This specification signed and witnessed this 30th day of September, 1916.

FRANZ A. FULLER.
